UNITED STATES PATENT OFFICE

LAURENCE E. TOPHAM, OF WENHAM, MASSACHUSETTS, ASSIGNOR TO UNITED SHOE MACHINERY CORPORATION, OF PATERSON, NEW JERSEY, A CORPORATION OF NEW JERSEY

SHOE SEWING MACHINE

Application filed March 27, 1928. Serial No. 265,189.

The present invention relates primarily to shoe sewing machines and is herein disclosed as embodied in a machine adapted to sew the outseam connecting the outsole with the welt, lasted upper and insole of a Goodyear welt shoe.

While all the features of the present invention are particularly applicable to sewing machines adapted to sew the outseams of shoes, certain features of the invention and particularly those relating to the mechanism for feeding the work are capable of embodiment in other types of sewing machines or in machines for performing upon 15 shoes or upon material to be incorporated in shoes, operations other than sewing.

The illustrated machine in which the several features of the present invention have been embodied is of the same general type 20 as that disclosed in the patent to French and Meyer, No. 473,870 dated April 26, 1892. The stitch forming and work feeding devices of machines of this type include a needle, an awl, a work support and a presser foot, and 25 these devices are arranged to act intermittently on the work, some or all of the devices being reciprocated back and forth in the line of feed, and while in engagement with the work, acting to feed the work. In 30 the machine of the French and Meyer patent, above referred to, the awl is utilized to feed the work and this is the only part which moves in the direction of feed while in engagement with the work. In this machine, 35 therefore, the feeding of the work is intermittent and takes place only during that portion of the stitch forming and work feeding cycle in which the awl is in engagement with the work.

40 In order to give more time during the cycle of stitch forming and work feeding operations for the movement of various parts of the machine so as to make the various motions easier and enable the machines 45 to be run more smoothly and at a higher speed, machines of this general type have been devised in which the stitch forming and work feeding devices have been arranged so that the feed is produced by a number of 50 devices acting alternately on the work, cer-

tain of the devices being backfed while other devices are in engagement with and feeding the work. The feeding period is thus lengthened out and a marked increase in the ease and speed of operation of the machine is secured. In certain machines, as for instance the machine disclosed in the patent to Topham No. 1,289,812, dated December 31, 1918, the devices which intermittently and alternately engage and feed the work are so timed that the length of the feeding period is increased to such an extent as to make the feed of the work continuous.

To actuate alternately the devices which feed the work two or more mechanisms for reciprocating the devices in the line of feed are required and in order to preserve the character of the feed, as for instance a non-varying uniform continuous feed, as well as to maintain the proper cooperation of the devices, a change in the adjustment of both mechanisms is required whenever a change is to be made in the length of the individual stitches. In machines as heretofore constructed the mechanisms for reciprocating the feeding devices have been so arranged that a separate and independent adjusting device was necessary for each mechanism and as a consequence it was impossible to change from one stitch length to another 50 during the sewing of a shoe or to make a change in the stitch length at any time even with the machine idle without the expenditure of a considerable amount of time and the exercise of great care on the part 55 of the operator.

An important feature of the present invention is embodied in a means for obviating this effect, devices intermittently acting on the work and mounted to reciprocate in the line of feed being utilized to feed the work as in prior constructions, but the mechanisms for reciprocating these devices in the line of feed being arranged so as to be capable of simultaneous adjustment, and an adjusting 90 means common to all of said mechanisms being provided whereby said mechanisms can be adjusted simultaneously. In a continuous feed machine embodying this feature of the present invention, the feeding mechanism can 95 100

be readily adjusted to vary the spacing of the work for the successive operations, as for instance to vary the length of the individual stitches while maintaining a uniform 5 and unvarying as well as continuous feed of the work. Also, where the feed is not continuous, the characteristics of the feeding movement can be maintained always the same regardless of any change in the length of the 10 spacing between successive stitch forming or other operations on the work. As has been suggested, this feature of the invention in its broader aspects is applicable to sewing machines other than those adapted for outside 15 stitching and to machines for performing operations other than sewing upon shoes or shoe materials.

To still further increase the speed, ease and smoothness of operation of machines of the 20 type disclosed in the patent to French and Meyer, above referred to, it has been proposed to time the operation of the various parts of the machine so that the awl is caused to enter the work after the needle has withdrawn with 25 the loop of thread and to withdraw from the work before the takeup sets the stitch. A machine having its various parts constructed and arranged to operate in this manner is disclosed in the patent to Topham, No. 30 1,462,587, dated July 24, 1923. The machine hereinafter described as embodying the several features of the present invention is also constructed and arranged to operate in this manner, the awl being timed to enter the work 35 after the needle withdraws with its loop of thread, and before the needle loop has been drawn down from the shuttle. In machines having the needle and awl timed in this manner, if the machine is stopped at the completion 40 of the sewing operation with both the needle and the awl out of the work and with the needle free of thread to permit the removal of the work, the machine must be manipulated by the operator before a new 45 piece of work is inserted in the machine so as to bring the awl into position to immediately enter the work when the machine is started, as otherwise upon starting the machine the needle will at once enter the work 50 and be liable to become bent or broken by reason of the fact that no awl hole has been made in the work to receive it. An object of the present invention is to relieve the operator of the necessity of manipulating the machine 55 in this manner and accordingly another important feature of the present invention contemplates the provision in an outseam lock-stitch sewing machine in which the awl is arranged to enter the work after the needle withdraws with its loop of thread and before 60 the needle loop is withdrawn from the shuttle, of mechanism cooperating with the moving parts of the machine to bring the machine to rest after the needle loop has been drawn 65 down from the shuttle, with the needle free

of the thread, and at a point in the cycle so that when the machine is again started the awl will immediately enter the work. This feature of the invention contemplates securing this result in any desired manner. In 70 the embodiment of the invention hereinafter described a stop mechanism is provided which acts when thrown into operation to reverse the direction of rotation of the cam shaft of the machine after the needle loop 75 has been drawn from the shuttle and to finally stop the cam shaft with the awl at a point in the cycle of operations of the machine at which the awl, in a forward cycle, is about to enter the work. 80

Other features of the invention which are particularly applicable to an outseam shoe sewing machine relate to an improved mechanism for actuating the needle guide, to an improved mechanism for actuating a work 85 cutting knife such, for instance, as a knife for cutting a stitch receiving groove in the welt, an improved construction and arrangement of edge gage with its actuating and controlling mechanism, and to improved 90 constructions and arrangements of parts for lifting the presser foot, opening the thread clamp and releasing the needle thread tension.

The several features of the present invention and the advantages secured thereby will be readily understood by those skilled in the art from the preceding discussion and from an inspection of the accompanying drawings 95 and the following specific description thereof. 100

Referring to the drawings, Fig. 1 is a view in front elevation of an outseam shoe sewing machine embodying the several features of the present invention, so much only of the machine being illustrated as is necessary to 105 show the connection of the present invention therewith; Fig. 2 is a detail sectional view on the line 2—2 of Fig. 1; Fig. 3 is a sectional end elevation of the machine, looking toward the right in Fig. 1; Fig. 4 is a detail view of a 110 portion of the mechanism for releasing the tension; Fig. 5 is a detail sectional plan view taken on the line 5—5 of Fig. 3 illustrating a portion of the mechanism for opening the thread clamp; Fig. 6 is a sectional end elevation of the machine looking toward the left in Fig. 1; Fig. 7 is a detail sectional view of a portion of the presser foot unlocking and lifting mechanism; Fig. 8 is a sectional plan view taken on the line 8—8 of Fig. 7; 120 Fig. 9 is a detail sectional view similar to Fig. 7 but showing the parts in a different position; Fig. 10 is a sectional plan view taken partly on the line 10—10 and partly on the line 10—11 of Fig. 9; Fig. 11 is a sectional end elevation of the machine looking 125 towards the right of Fig. 1, taken on a plane between the planes of Figs. 3 and 6; Figs. 12 and 13 are detail views illustrating a mechanism for actuating the needle guide; 130

Figs. 14 and 15 are detail views illustrating a portion of the connections for actuating the welt cutting knife from the awl segment; Fig. 16 is an end view of the machine partly 5 in section and with many parts omitted, looking from the right in Fig. 1; Fig. 17 is a detail view in front elevation partly in section of the two carriers by which the work feeding devices are reciprocated together 10 with their actuating mechanism; Fig. 18 is a detail view of an arm forming the portion of the connections for reciprocating the needle carrier; Fig. 19 is a view in front elevation of the needle carrier; Fig. 20 is a detail 15 sectional plan view taken on the line 20—20 of Fig. 17; Fig. 21 is a detail sectional plan view taken on the line 21—21 of Fig. 17; Fig. 22 is a detail view of the mechanism for actuating the slide by which the presser foot, work 20 support and awl are reciprocated, the link which is adjustably mounted on the slide being swung out of its normal position in order to more clearly show the link connections; Fig. 23 is a view similar to Fig. 22 of the 25 mechanism for actuating the needle carrier; Fig. 24 is a detail sectional view on the line 24—24 of Fig. 22; Fig. 25 is a detail sectional view on the line 25—25 of Fig. 23; Fig. 26 is a detail view in front elevation 30 partly in section illustrating particularly the presser foot and its associated parts; Fig. 27 is a detail sectional view on a somewhat smaller scale than Fig. 26 taken on the line 27—27 of said figure; Fig. 28 is a detail 35 sectional plan view taken on the line 28—28 of Fig. 26; Fig. 29 is a detail vertical sectional view taken on the line 29—29 of Fig. 26; Fig. 30 is a view in rear elevation of the machine illustrating particularly the driving and 40 stopping mechanism; Fig. 31 is a vertical sectional view of the machine looking towards the right in Fig. 30 and taken on a plane at the left of the driving and stopping mechanism; Fig. 32 is a detail sectional view 45 taken on a plane slightly to the left of the plane Fig. 31 in Fig. 30, illustrating particularly the positive stopping dog of the stop mechanism; Fig. 33 is a detail view of certain of the parts illustrated in Fig. 31, but looking in the opposite direction; Fig. 34 is a vertical longitudinal sectional view of the driving and stopping mechanism; Fig. 35 is a cross sectional view taken on the line 35—35 of Fig. 34; and Fig. 36 is a detail 50 cross sectional view taken on the line 36—36 of Fig. 34.

The curved hook needle of the machine is indicated at 38, the needle guide at 40, the awl at 42, the thread arm at 44, the loop spreader at 46, the looper at 48, the shuttle at 49, the takeup at 50, the auxiliary takeup at 52, the thread clamp at 54, the tension wheel at 56, the work support at 58 and the presser foot at 60, all of these parts except 55 as hereinafter specifically described having

substantially the same construction and arrangement, and being operated through the same mechanisms as in the machine disclosed in the patent to French and Meyer, No. 473, 70 870 hereinbefore referred to. As in the machine of the French and Meyer patent the needle is mounted in a segment 62. This segment instead of being actuated directly from the needle cam lever 64, however, is actuated thereby through two intermediate pins 75 66, as in the machine of the patent to Topham, No. 1,462,587. The awl is secured to an awl segment which is actuated as in the machine of the French and Meyer patent directly from the awl segment lever 68. 80

In the machine illustrated, the feed of the work is produced by the work support, presser foot and needle, these parts being mounted to move back and forth in the line of feed and being actuated to impart a continuous feeding movement to the work. To produce this continuous feeding movement the needle moves in the direction of feed while in engagement with the work and while the work is unclamped by the work support and presser foot, the back feed of the work support and presser foot taking place during the feeding movement of the needle. The work support and presser foot are relatively actuated to clamp the work and move in the direction of feed while the work is clamped to continue the feeding of the work, and during this feeding movement of the work support and presser foot the needle is back fed. The awl is mounted to move back and forth 90 in the line of feed with the work support and presser foot, being back fed while out of the work with the presser foot and work support, and being actuated to pierce the work during the feeding movement of the 95 work support and presser foot. 100

To reciprocate the work feeding devices back and forth in the line of feed, two carriers are provided on one of which the needle is mounted, and to the other of which the awl, the work support and the presser foot are connected. 110

The needle carrier (see Figs. 1, 2, 17 and 19) comprises a boss 70 in which the stud 72 forming the pivotal support of the needle segment is mounted, a portion 74 extending downwardly from the boss 70, a bar 76 extending rearwardly in the direction of feed from the portion 74, and a block 78 through the upper end of which the end of the bar 76 extends and to which it is adjustably connected by means of adjusting nuts 80 mounted on the bar and engaging the opposite sides of the block. At its forward end the needle carrier is supported by means of a link 82 which is pivotally mounted at its upper end on the machine frame by a pivot pin 84 passing through a perforation 86 in the link. The pivotal connection between the needle carrier and the link 82 is formed by a pivot 125 130

pin 88 secured in a perforation 90 in the link and passing through a perforation 92 in the needle carrier. At its rear end the needle carrier is supported by means of links 94 (see 5 Fig. 2) which are pivotally supported at their upper ends on the machine frame at 96 and pivotally connected at their lower ends to the block 78 at 98. The links 82 and 94 constitute, in effect, parallel supporting links 10 which permit a back and forth movement of the needle carrier to move the needle in a straight line in the line of feed.

The carrier reciprocating the work support and presser foot consists of a slide indicated at 100 mounted in the machine frame and having the same general shape as the feed slide of the machine of the French and Meyer Patent No. 473,870.

The carriers are reciprocated back and forth in the line of feed by two mechanisms each of which comprises a cam and connections from the cam to the carrier. The mechanism for reciprocating the slide 100 (see Figs. 1, to 16, 17, and 22) comprises an arm 102 having one end pivotally connected at 104 to the machine frame. The other end of the arm 102 is pivotally connected at 106 to one end of a link 108, the other end of which is pivotally connected 15 at 110 to a support 112 on the slide 100. With this construction a downward swinging movement of the arm 102 about the pivot 104 will move the slide 100 rearwardly in the line of feed and the upward swinging movement of the arm will move the slide forwardly in the direction of feed. To swing the arm, a link 114 is pivoted at its lower end at 106 to the arm, and at its upper end is pivotally connected to the horizontal arm 20 of a bell crank 116. This bell crank is pivotally mounted upon a pivot stud 118 and at the upper end of its vertical arm engages a cam groove in a cam disc 120 on the cam shaft 122 of the machine. The mechanism 25 for reciprocating the needle carrier is similar to that for reciprocating the slide 100 and comprises a swinging arm 124 having its upper end pivotally connected at 110 to the support 112 on the slide 100, and having its lower end connected by a link 126 to arms 30 projecting rearwardly from the block 78 which forms a part of the needle carrier. The arm 124 at its pivotal connection with the link 126 is connected to the lower end 35 of a link 128, the upper end of which is connected to the horizontal arm of a bell crank 130. This bell crank is also mounted on the pivot stud 118 which supports the bell crank 116 and is engaged at the upper end of its 40 vertical arm by another cam groove in the cam disc 120 formed in the disc inside of the groove which actuates the bell crank 116. With this construction, a portion of the mechanism for actuating the needle carrier 45 forms a connection between the slide 100 and

the needle carrier so that the needle carrier is moved back and forth with the slide by the slide reciprocating mechanism and is moved by its actuating mechanism with relation to the slide.

70

It will be seen that each of the carrier reciprocating mechanisms can be adjusted to vary the movement of the carrier actuated by it, by changing the position of the pivotal point 110, and since this point is common to both mechanisms a movement of this point will adjust simultaneously and in a corresponding manner both mechanisms. In the construction shown, an adjustment of the point 110 is secured by adjustably mounting 75 the support 112 on the slide 100. The support 112 is in the form of a yoke having the pivotal connection 110 for the link 108 and arm 124 at its upper end and having its downwardly and rearwardly extending arms 80 pivotally mounted upon ears projecting upwardly from the slide 100. One arm of the yoke shaped support 112 extends downwardly beyond its pivot as best shown in Figs. 16 and 17 and is provided with segmental bevel gear teeth meshing with corresponding segmental bevel gear teeth formed on the upper end of a short vertical shaft 132 mounted in the slide 100. To the lower end of the shaft 132 a manually operable lever 134 is secured which lever extends rearwardly and at its outer end is formed to embrace a perforated guiding segment 136. The connections from the lever 134 to the yoke shaped support 112 serve to lock the support in adjusted position and constitute a convenient means by which both carrier reciprocating mechanisms can be simultaneously adjusted during the operation of the machine or at any other time as the operator may desire. 90 Pins 138 may be inserted in the perforations in the plate 136 to limit the movement of the adjusting lever 134 to any desired extent.

The needle segment is mounted directly on the pivot stud 72 and the needle guide is mounted on the hub of the needle segment. For actuating the needle guide a novel and improved mechanism is provided whereby the needle guide can be driven frictionally to cause it to move towards and from the work and also can be given a forward movement with relation to the needle to cover the empty hook of the needle after the loop of needle thread has been taken from the hook, and thereby prevent the needle thread from catching on the barb of the hook during the continued manipulation of the thread in forming the stitch. The needle guide actuating mechanism also includes a new and improved means for driving the needle guide frictionally from the needle segment. The needle guide actuating mechanism is best shown in Figs. 12 and 13. As shown in these figures, the needle guide is provided with an arm ex- 115 120 125 130 135

tending radially in the opposite direction from the portion engaging the needle, in the outer end of which is mounted a friction shoe 140. This shoe is forced outwardly by a spring 142 set in a recess in the arm against a friction surface 144 formed on the needle segment concentric with the axis of the segment. A simple, reliable and efficient connection is thus provided between the needle segment and the needle guide which will act to move the needle guide frictionally back and forth and against the upper surface of the presser foot regardless of the varying thickness of the work.

After the needle loop has been taken from the needle, it is desirable to advance the needle guide to close the needle hook and thereby prevent the thread from catching on the barb of the needle during the continued manipulation of the thread in forming the stitch. Accordingly, means are provided for imparting such a movement to the needle guide. As a convenient means for producing this movement the thread arm is utilized in the illustrated construction, a projection 146 being provided on the needle guide arranged to extend into a notch 148 formed on the thread arm slide when the needle guide is in its retracted position, and a movement being imparted to the thread arm at the proper point in the cycle of operations to cause the lower end of the notch to engage the projection and move the needle guide with relation to the needle as indicated in Fig. 11.

The work support 58 is of usual construction and is mounted upon a standard 150 which rises from the forward end of the slide 100. The work support thus moves with the slide 100 back and forth in the line of feed. The awl segment is also mounted in the standard 150 as usual in outseam shoe sewing machines. The presser foot 60 (see Figs. 6, 26, 28, and 29) is secured to the front portion 152 of the presser foot lever. The presser foot lever is pivotally mounted upon a hollow bushing 154 secured in a projection 156 forming a portion of the machine frame. The presser foot, as has been stated, is arranged to reciprocate back and forth in the line of feed with the work support and to allow it to so move the presser foot lever is made in two parts, the rear portion 158 being mounted on the bushing 154 so as to be held against movement with the slide 100 and the front portion 152 of the lever being mounted to slide with relation to the rear portion. The front portion of the lever is formed at its rear end to straddle the front end of the rear portion and is provided with a supporting pivot pin 160 extending through the hollow bushing 154. Guiding surfaces indicated at 162 and a depending rib 164 formed on the rear end of the front portion of the lever engage corresponding surfaces and a corresponding recess formed on the front end of the rear portion of the lever and cooperate with the pin 160 in securely connecting the two portions of the lever together while permitting the relative sliding movement back and forth in the line of feed. To cause the front portion of the lever to move with the feed slide 100 a segmental flange 166 is formed on the front portion and engages a corresponding recess 75 in the standard 150 of the slide 100.

The mechanism for actuating the presser foot lever and for locking the lever with the presser foot in engagement with the work is similar to that disclosed in the patent to French and Meyer hereinbefore referred to and comprises actuating and locking pawls 168 and 170 engaging respectively the actuating lever 172 (see Fig. 6) and the rear portion of the presser foot lever 158.

An efficient and novel mechanism is provided, however, for unlocking and lifting the presser foot manually, and also for unlocking and lifting the presser foot automatically upon stopping the machine. The mechanism for unlocking and lifting the presser foot comprises a lifting lever 174 (see Figs. 16, 26 and 27) pivotally mounted upon a portion of the machine frame and having its forward end extending into convenient position to be manipulated by the operator while its rear end extends over the harp shaped member 176 pivotally supported upon the rear end of the presser foot lever 158 and forming a part of the usual thread measuring mechanism. With this arrangement of the lever 174 a downward movement of its rear end depresses the rear end of the lever 158 after the pawls 168 and 170 have been moved out of engagement with their cooperating ratchets and lifts the presser foot from the work. In order to move the pawls 168 and 170 into inoperative position so as to allow the presser foot to be lifted a pawl disengaging member 178 is provided mounted to slide in a substantially horizontal direction and provided with arms at its rear end adapted to engage pins on the pawls and move the pawls to an inoperative position when a rear movement is imparted to the member 178. At its forward end the member 178 is mounted in a slot formed in a web 180 forming a part of the machine frame. On each side of the web 180 the member 178 is provided with a projecting flange 182 which flanges limit the movement 120 of the member 178 in each direction as clearly shown in Figs. 7, 8, 9 and 10. For moving the member 178 forwardly and backwardly an actuating member 184 is provided pivotally mounted upon the bushing 154. An actuating connection between the member 184 and the member 178 is formed by a segmental portion of the member 184 which extends through the slot in the web 180 at one side of the member 178. A ball 186 is seated in

a perforation in the member 178 which ball cooperates with a recess 188 formed in the member 184 and with a recess 192 formed in one wall of the web 180. The member 184 is actuated from the lifting lever 174 through a pin 194 projecting from the member 184 through a slot 196 in a flange projecting from the hub of the lifting lever. The construction and arrangement of the connections between the lifting lever and the pawl releasing member 178 are such that during the first portion of the downward movement of the rear end of the lever 174 the member 184 is moved from the position indicated in Figs. 7 and 8 to a position in which the ball 186 is in engagement with the recess 192 in the web 180. The member 178 is thus moved to release the pawls 168 and 170 from their ratchets before the rear end of the lever 174 comes in contact with the harp shaped member 176. As the ball 186 enters the recess 192 further movement of the member 178 is prevented by the engagement of a flange 182 with the web 180 and a continued movement of the member 184 is permitted during the continued movement of the lifting lever 174 in lifting the presser foot from the work. The final position of the parts when the presser foot has been lifted from the work is indicated in Figs. 9 and 10. The return movement of the lifting lever 174 to permit the presser foot to again engage the work first moves the member 184 from the position indicated in Figs. 9 and 10 while the member 178 remains stationary and finally after the recess 188 in the member 184 comes opposite the recess 192 the ball 186 enters recess 188 and the forward end of the member 184 engages a flange 198 on the forward end of the member 178 and returns the member 178 to its original position indicated in Figs. 7 and 8. To unlock and lift the presser foot automatically upon stopping the machine a vertically arranged rod 200 is provided as indicated in Fig. 16, which extends through a perforation in the rear end of the lever 174. This rod is depressed upon stopping the machine through connections from the stopping mechanism hereinafter described and when so depressed actuates the lifting lever 174 to unlock and lift the presser foot by the engagement of a collar 202 secured to the lower end of the rod above the rear end of the lever 174. A knife for cutting a stitch receiving groove or slit in the work is indicated at 204. This knife consists of a rod the upper end of which is adapted to extend through the slot in the work support and the lower end of which is clamped so as to be vertically adjustable in a holder 206. In order to permit the knife to be thrown into and out of operation the holder 206 is pivotally mounted upon a carrier 208 which in turn is pivotally mounted upon a pivot stud 210 on the slide 100. The carrier 208 is moved to

raise and lower the knife 204 into and out of operating position by means of a slide 216 mounted in the slide 100 and provided with a vertically arranged groove in which a downwardly extending arm 218 of the carrier 208 engages. The slide 216 has a screw threaded engagement with one end of a screw threaded shaft 220, the other end of which has a screw threaded engagement with a bushing 222 rigidly secured in the slide 100. The arrangement of the slide 216 and the shaft 220 is such, as clearly illustrated in Figs. 17, 20 and 21, that a rotation of the shaft in opposite directions reciprocates the slide 216 back and forth and through the carrier 208 moves the cutter 204 into and out of operating position. For rotating the shaft 220 a cross slide 224 is mounted in the slide 100 and is provided with rack teeth engaging a pinion formed on the shaft 220. The forward end of the cross slide 224 is engaged by the end of an arm 226 projecting from a short vertical rock shaft 228 to the lower end of which an actuating lever arm 230 is secured. This lever may be actuated directly or through connections to the feed adjusting lever 134 as will be hereinafter described.

To lessen the drag of the knife 204 upon the work and especially to relieve so far as possible the strain on the needle in feeding the work, the knife 204 is arranged to move with the work while the work is being fed by the needle and to be actuated to cut the work while the work is clamped and being fed by the work support and presser foot. The movement of the knife with the work is permitted by the pivotal connection of the holder 206 with the carrier 208 and a cutting movement is imparted to the knife by mechanism which comprises a lever 232 pivotally mounted upon the pivot pin 210 and provided at its upper end with a slot 234 through which the knife 204 passes. A spring 236 connected to an arm 238 projecting from the lever 232 tends to hold the lever in a position which permits the knife to move with the work while being fed by the needle. Movement in the opposite direction against the tension of the spring 236 is imparted to the lever 232 to cause the knife to cut the work by a cam shaped projection 240 formed on an arm projecting from a rock shaft 242 mounted in the slide 100, which projection engages a roll 244 mounted on the upper end of the lever 232. The rock shaft 242 is provided with a rearwardly extending arm 246 which carries a wedge shaped projection 248 (see Figs. 11, 14 and 15) arranged to engage a cam groove 250 formed in the side of the awl segment cam lever 68. Through the connections described, therefore, the knife 204 is actuated to cut the work in timed relation to the movement of the awl and is moved in a direction opposite to the direction of

feed before the awl enters the work so as to be out of the path of movement of the awl. This movement takes place while the work is clamped between the work support and 5 presser foot. As the awl withdraws from the work the awl segment cam lever moves to the position indicated in Fig. 15 allowing the shaft 242 to be rocked by a spring 252 connected to an arm on the rock shaft so 10 as to release the lever 232.

The edge gage of the machine is indicated at 254 and comprises an arm extending laterally from the upper end of a vertical rock shaft 256 mounted in the standard 150 of the 15 slide 100. The lower end of the rock shaft is provided with gear teeth which mesh with rack teeth formed on the slide 216 so that a rocking movement is imparted to the rock shaft whenever the slide 216 is moved, as 20 hereinbefore described. This rocking movement of the rock shaft moves the edge gage back and forth transversely of the line of feed to vary the position of the outseam on 25 a shoe in the manner customary in the sewing of Goodyear welt shoes.

It is a common practice in sewing the outseams of Goodyear welt shoes to change the length of stitch in passing from the shank portion of a shoe on to the fore part, to move 30 the edge gage forward at this time, and also to move the knife which cuts a stitch receiving groove or slit in the welt into operative position and to reverse these operations in passing from the fore part back into the shank. To enable the machine illustrated in 35 the drawings to be operated in this manner the actuating lever arm 230 hereinbefore referred to is connected to the feed adjusting lever 134 and in order that the edge gage may 40 be locked securely in advanced position against any possibility of displacement, a locking device is provided for locking the actuating lever arm in one of its positions. In the illustrated construction (see Figs. 1, 20 45 and 21) a latch 258 is pivotally mounted on the outer end of the actuating lever arm 230 so as to have a limited movement with relation to the arm and is connected at its outer end by means of a link 260 to the feed adjusting lever 134. The inner end of the latch 50 55 60 65 70 75 80 85 90 95 100 105 110 115 120 125 130 258 is shaped to engage a notch in a locking plate 262 adjustably clamped on the lower end of the bearing for the vertical rock shaft 228. A spring 264 connected to the inner end 55 of the latch tends to move the latch in a direction to engage the locking plate. Except for the locking notch the surface of the locking plate engaged by the inner end of the latch 258 is concentric with the pivot shaft 228 and whenever the latch 258 is actuated its movement in one direction with relation to the lever arm 230 is limited by engagement of the latch with the locking plate. The movement of the latch 258 in the opposite direction with relation to the lever arm 230

is limited by a projection 266 on the arm. The actuating lever arm 230 is thus locked, unlocked and actuated by movements transmitted to the latch from the feed adjusting lever.

The driving and stopping mechanism of the machine comprises a forwardly driving friction clutch which normally drives the machine at a high speed during the sewing operation, a reversely driving friction clutch which is thrown into operation in stopping the machine which retards, stops and reversely rotates the cam shaft at a low speed to final stopping position, and a timing cam for throwing the reversely driving friction clutch into and out of operation.

The high speed forwardly driving friction clutch comprises a clutch surface formed on the driving pulley 268 and a cooperating friction surface on the hand wheel 270. The hand wheel is rigidly secured to a sleeve 272 keyed to the cam shaft 122, and the pulley 268 is mounted to rotate loosely and slide on the sleeve 272. The driving pulley 268 is moved into and out of engagement with the hand wheel 270 by a clutch shifting lever 274 one end of which engages the hub of the pulley 268 and the other end of which extends between collars 276 secured to the rod 278 connected to the starting and stopping treadle.

The reversely driving clutch which is thrown into operation in stopping the machine comprises a driven clutch member 280 integral with a sleeve 282 mounted on the sleeve 272 and a driving clutch member 284 mounted to rotate loosely on the sleeve 272, and driven continuously at a comparatively low speed by a continuously rotating worm shaft 286 engaging a worm wheel formed on the driving clutch member. The worm 286 is driven by a belt passing over a pulley 288 secured to the rear end of the shaft carrying the worm 286. The driven clutch member 280 of the reverse driving clutch is connected to the hand wheel 270 so as to rotate at all times with the hand wheel and with the cam shaft 122 but is mounted to slide longitudinally on the sleeve 272 and is normally held out of engagement with the driving clutch member 284 by springs 290 acting on plungers secured to a flange 292 rigid with the member 280 and operating within hollow studs 294 secured to the hand wheel 270 and projecting into perforations formed in the flange 292. While the members 268 and 270 are in engagement and the cam shaft is being driven in a forward direction the clutch members 280 and 284 are out of engagement and rotating in opposite directions.

The timing cam for moving the clutch member 280 into and out of engagement with the reversely rotating clutch member 284 is indicated at 296 and is mounted on the clutch member 280 so as to move longitudinally

therewith and except as hereinafter described to rotate with said clutch member. The groove of the timing cam is engaged by one end of a horizontally arranged bell crank 298 which, while the cam shaft is being driven by the forwardly driving clutch, is vibrated idly so that the cam has no effect on the clutch member 280 of the reverse driving clutch and the members of the reverse driving clutch remain out of engagement. The other end of the bell crank 298 extends over a vertically movable bolt 300 and is provided with a perforation into which the bolt 300 can rise when allowed to do so. This occurs after the forward driving clutch is thrown out of operation by the upward movement of the treadle rod 278. The bell crank 298 is thus held against movement during the continued rotation of the cam shaft 122 under its momentum, the cam 296 together with the member 280 of the reverse driving clutch is forced to the left into the position illustrated in Fig. 34, and thereby the reverse driving clutch is thrown into operation. The reversing clutch acts first as a friction brake to retard and stop the forward rotation of the cam shaft 122 and then drives the cam shaft backwardly until the clutch members are thrown out by the action of the timing cam 296.

As has been stated the stitch forming devices of the machine are timed so that the awl enters the work after the needle withdraws from the work with its loop of thread and before the needle loop is drawn from the shuttle, and withdraws from the work before the stitch is set by the takeup. In order that the machine may be stopped after the loop of needle thread has been drawn from the shuttle the timing cam and reverse driving clutch are so constructed that the reversal in the direction of rotation of the cam shaft takes place at this point in the cycle of operations and in order that the cam shaft may be finally stopped in the position in which the awl will at once enter the work when the machine is again thrown into operation the reverse rotation of the cam shaft is continued until the awl during such reverse rotation has entered and again withdrawn from the work. To permit this backward rotation of the cam shaft and cause the timing cam to disconnect the members of the reverse clutch at the proper point in the rotation of the shaft the timing cam 296 is mounted on the driven member 280 of the reverse driving clutch through a lost motion connection which permits a certain amount of angular movement of the clutch member 60 with relation to the cam. This lost motion connection comprises a radially arranged key 302 (see Figs. 35 and 36) secured in the cam and projecting into a segmental recess 304 in the sleeve portion of the clutch member 65 280 upon which the cam is mounted to have

a rotary movement limited by the ends of the segmental recess.

As the driven member 280 of the reverse driving clutch starts to rotate in a reverse direction the timing cam tends to rotate with the clutch member. Accordingly a latch 306 is provided pivotally mounted in the frame of the machine and arranged to engage the outer end of the key 302 and hold the timing cam against rotation during the first portion of the reverse rotation of the clutch member. The latch 306 is provided with a pin 308 which bears against a cam 310 formed on the clutch member 280 and this cam operates to lift the latch 306 out of engagement with the key 302 before the key is engaged by the rear end of the recess 304. After the reverse driving clutch is thrown out, the cam shaft is positively stopped in its final position by a stop dog 312 (see Fig. 32) which engages a stop shoulder formed on one of the cam discs 314 of the machine.

The locking pin or lock bolt 300 is mounted in a horizontally arranged spring pressed carrier 316 and is controlled from the treadle rod 278 through connections which comprise an arm 318 (see Figs. 31 and 33) pivotally mounted on the machine frame and connected to the upper end of the treadle rod. At its outer end the arm 318 is provided with a cam surface arranged when the treadle rod is depressed to engage a roll 320 on a lever arm 322 and swing said lever arm downwardly. A lever arm 324 is formed integrally with the arm 322 and is connected by a link 326 to the lower end of the lock bolt 300. The lock bolt is acted upon by a spring 328 which raises the bolt into engagement with the bell crank 298 when the treadle rod 278 is allowed to rise and the bolt is lowered out of engagement with the bell crank through the connections described when the rod is depressed.

The latch 306 is forced into the path of the key 302 by a spring 330 connected with a rearward extension from the latch. In order to hold the latch out of the path of movement of the key 302 during the normal forward rotation of the cam shaft and out of engagement with the cam 310 the latch is secured to a rock shaft 332 to which is also secured an arm 334 which extends into a position to be engaged by a roll 336 on the arm 322.

In throwing the reverse driving clutch into operation a slight movement to the right as viewed in Fig. 31 is imparted to the lock bolt carrier 316 from the timing cam 296. In the machine illustrated this movement of the lock bolt carrier is utilized to lift the presser foot, release the tension and open the thread clamp. To this end a rock shaft 338 is mounted in the carrier 316 and is provided at one end with a spring pressed pawl 340 arranged to be engaged by a detent 342 on

the arm 318 when the arm is in its uppermost position. To the other end of the rock shaft 338 an arm 344 is secured which arm is swung upwardly by the rocking of the shaft 338 when the pawl 340 engages the detent 342 during the movement of the lock bolt carrier 316 as the reverse clutch is thrown into operation. The arm 344 at its outer end is pivotally connected to the lower end of a link 346, the upper end of which is connected to a lever arm 348 projecting from a rock shaft 350 mounted in the upper portion of the machine frame. An arm 352 projecting from the rock shaft 350 is connected to the upper end of the rod 200 and the arrangement of the lever arms 352 and 348 is such that as the arm 344 moves upwardly the rod 200 is depressed thereby unlocking and raising the presser foot as hereinbefore described.

To the arm 344 is also pivotally connected a link 354, the lower end of which is connected to an arm 356 projecting from a rock shaft 358. To this rock shaft is secured an arm 360 (see Figs. 3 and 5) the forward end of which has a slotted connection with the center joint of toggle links 362 which links are normally in line and form the connection between the thread clamp cam 366 on the rock shaft 368 through which the thread clamp is actuated as in the machine of the French and Meyer patent. With this construction upon stopping the machine, the shaft 358 is rocked to move the arm 360 downwardly thereby breaking the toggle joint formed by the links 362 and opening the thread clamp.

Simultaneously with the lifting of the presser foot and the opening of the thread clamp upon stopping the machine the tension on the needle thread is released through connections from the rock shaft 368. To release the tension the upper end of a rod 370 is connected to an arm 372 on the rock shaft 368 and the lower end of this rod is connected to the horizontal arm of a bell crank 374. The bell crank 374 is pivotally mounted in a block 376 through which the stationary stud 378 on which the tension wheel 56 is mounted passes. The upper end of the vertical arm of the bell crank 374 engages a slot in the stud 378 so that this end of the bell crank is held stationary and as the rod 370 is raised by the rocking of the shaft 368 in stopping the machine, the bell crank is moved bodily and the block 376 is moved out of frictional engagement with the tension wheel 56 against which it is normally pressed by the tension spring 380.

The stop dog 312 (see Figs. 31 and 32) is secured to a pivot shaft 382 and is forced towards the cam disc 314 by a spring 384 one end of which is connected to the link 354 and the other end of which is connected to an arm 386 secured to the rock shaft 382. The outer end

of the arm 386 engages beneath a shoulder 388 on the link 354 and by reason of this construction the stop dog 312 is held out of engagement with the cam disc 314 while the machine is in operation and is permitted to move into engagement with the disc as the link 354 rises during the operation of the stopping mechanism.

Certain features of the machine herein described, relating more particularly to the stopping mechanism, the presser-foot lifting mechanism and the edge gage mechanism form the subject-matter of divisional applications Serial No. 375,444 filed July 2, 1929, Serial No. 639,459 filed October 25, 1932, and Serial No. 639,460, filed October 25, 1932.

The nature and scope of the invention having been indicated and a specific embodiment of the several features of the invention having been described what is claimed is:

1. In a machine provided with devices engaging the work and acting intermittently to perform an operation on the work and feed the work, carriers to which said devices are connected arranged to reciprocate along the line of feed, mechanisms for actuating said devices and reciprocating said carriers to impart a continuous feeding movement to the work, and adjusting means common to said carrier reciprocating mechanisms for adjusting said mechanisms simultaneously.

2. In a machine provided with devices engaging the work and acting intermittently to perform an operation on the work and feed the work, carriers to which said devices are connected arranged to reciprocate along the line of feed, mechanisms for actuating said devices and reciprocating said carriers to feed the work and cause each carrier to be back fed during the feeding movement of another carrier, and adjusting means common to said carrier reciprocating mechanisms for adjusting said mechanisms simultaneously.

3. In a machine provided with devices engaging the work intermittently to perform an operation on the work and feed the work, means for actuating said devices to engage the work, a plurality of mechanisms for reciprocating said devices along the line of feed to impart a continuous feeding movement to the work, and adjusting means common to said mechanisms for adjusting said mechanisms simultaneously.

4. In a machine provided with devices engaging the work intermittently to perform an operation on the work and feed the work, means for actuating said devices to engage the work, a plurality of mechanisms for reciprocating said devices along the line of feed timed to back-feed certain of said devices during the feeding movement of other of said devices, and adjusting means common to said mechanisms for adjusting said mechanisms simultaneously.

5. A sewing machine having, in combina-

tion, stitch forming and work feeding mechanisms including devices intermittently acting on the work, and mounted to reciprocate in the line of feed, mechanisms for actuating and reciprocating said devices to feed the work continuously during the sewing, and adjusting means common to said mechanisms for adjusting said mechanisms simultaneously.

10. 6. A sewing machine having, in combination, stitch forming and work feeding mechanism including devices intermittently and alternately acting on the work, mechanisms for moving the devices in the direction of feed while in active engagement with the work, and for alternately moving them in the opposite direction while out of active engagement therewith, and adjusting means common to said mechanisms for adjusting said mechanisms simultaneously.

20. 7. A sewing machine having, in combination, stitch forming mechanism comprising a needle, an awl, a work support and a presser foot, two carriers to which said parts are connected, a connection between the carriers to cause one to be moved by the other, mechanism for reciprocating one of the carriers in the line of feed, mechanism for imparting a reciprocation to the carriers relative to each other in the line of feed, and adjusting means common to said mechanisms for adjusting said mechanisms simultaneously.

35. 8. A sewing machine having, in combination, stitch forming and work feeding devices including a needle, an awl, a work support and a presser foot, a plurality of mechanisms for reciprocating said devices along the line of feed timed to back feed certain of said devices during the feeding movement of other of said devices, and adjusting means common to said mechanisms for adjusting said mechanisms simultaneously.

45. 9. A sewing machine having, in combination, stitch forming and work feeding devices including a needle, an awl, a work support, and a presser foot, a plurality of mechanisms for reciprocating said devices along the line of feed to impart a continuous feeding movement to the work, and adjusting means common to said mechanisms for adjusting said mechanisms simultaneously.

55. 10. A sewing machine having, in combination, stitch forming and work feeding devices including a needle, an awl, a work support and a presser foot, two carriers to which said devices are connected arranged to reciprocate along the line of feed, mechanisms for actuating said devices and reciprocating said carriers to impart a continuous feeding movement to the work, and adjusting means common to said carrier reciprocating mechanisms for adjusting said mechanisms simultaneously.

65. 11. In a machine provided with devices engaging the work and acting intermittently

70. ly to perform an operation on the work and feed the work, two carriers to which said devices are connected arranged to reciprocate along the line of feed, mechanism for reciprocating one carrier, a connection between said carrier and the second carrier to cause said second carrier to move with the first, mechanism for reciprocating the second carrier with relation to the first carrier, and adjusting means common to said mechanisms for adjusting said mechanisms simultaneously.

75. 12. In a machine provided with devices engaging the work and acting intermittently to perform an operation on the work and feed the work, two carriers to which said devices are connected arranged to reciprocate along the line of feed, mechanism for reciprocating one carrier, mechanism mounted on said carrier for reciprocating the second carrier with relation to the first, and arranged to move the second carrier with the first, and adjusting means common to said mechanisms for adjusting said mechanisms simultaneously.

80. 13. In a machine provided with devices engaging the work intermittently to perform an operation on the work and feed the work, two carriers to which said devices are connected arranged to reciprocate along the line of feed, a swinging arm pivotally mounted at one end to swing about a fixed pivot, a link connecting the other end of said swinging arm and one of the carriers, a cam and suitable connections for swinging said arm, a swinging arm pivotally mounted at one end on said carrier, a link connecting the other end of said second swinging arm and the second carrier, a cam and suitable connections for swinging said second mentioned arm, and means for adjusting the pivotal connections on the first mentioned carrier to vary the movements imparted to both carriers.

85. 14. In a machine provided with devices 110. engaging the work intermittently to perform an operation on the work and feed the work, two carriers to which said devices are connected arranged to reciprocate along the line of feed, a swinging arm pivotally mounted at one end to swing about a fixed pivot, a link connecting the other end of said swinging arm and one of the carriers, a cam and suitable connections for swinging said arm, a swinging arm pivotally mounted at one end concentric with the pivotal connection of the first mentioned swinging arm and the carrier, a link connecting the other end of said second swinging arm and the second carrier, said arms and links all being of the same length, a cam and suitable connections for swinging said second mentioned arm, and means for adjusting the pivotal connections on the first mentioned carrier to 115. 120. 125. 130.

vary the movements imparted to both carriers.

15. A sewing machine having, in combination, stitch forming and work feeding devices including a work piercing needle, a work piercing awl, a work support and a presser foot, two carriers to which said devices are connected arranged to reciprocate along the line of feed, the presser foot and work support being connected to one of said carriers and at least one of said work piercing instruments being connected to the second carrier, mechanisms for actuating said devices and reciprocating said carriers to impart a continuous feeding movement to the work, timed to back feed the work support and presser foot carrier while said last mentioned work piercing instrument is in the work, and adjusting means common to said carrier reciprocating mechanisms for adjusting said mechanisms simultaneously.

16. A sewing machine having, in combination, stitch forming and work feeding devices including a needle, an awl, a work support and a presser foot, two carriers to which said devices are connected arranged to reciprocate along the line of feed, the presser foot and work support being connected to one carrier and the needle being connected to the other carrier, mechanisms for actuating said devices and reciprocating said carriers to impart a continuous feeding movement to the work timed to back feed the work support and presser foot carrier while the needle is in the work, and adjusting means common to said carrier reciprocating mechanisms for adjusting said mechanisms simultaneously.

17. A sewing machine having, in combination, stitch forming and work feeding devices including a needle, an awl, a work support and a presser foot, two carriers to which said devices are connected arranged to reciprocate along the line of feed, the presser foot and work support being connected to one carrier and the needle being connected to the other carrier, a connection between the carriers to cause one to be moved by the other, and mechanisms for reciprocating one of said carriers in the line of feed and for imparting a reciprocation to the carriers relative to each other in the line of feed timed to impart a continuous feeding movement to the work and to back feed the work support and presser foot carrier while the needle is in the work.

18. A sewing machine having, in combination, stitch forming and work feeding devices including a needle, an awl, a work support and a presser foot, means for actuating the work support and presser foot to clamp and feed the work, means for actuating the needle to feed the work during the back feed of the work support and presser foot, a work engaging knife arranged to move with the work while being fed by the needle, and

means for actuating the knife in the line of feed to cut the work while clamped.

19. A sewing machine having, in combination, stitch forming and work feeding devices including a needle, an awl, a work support and a presser foot, two carriers to which said devices are connected arranged to reciprocate along the line of feed, the presser foot and work support being connected to one carrier and the needle being connected to the other carrier, mechanisms for actuating said devices and reciprocating said carriers to impart a continuous feeding movement to the work timed to back feed the work support and presser foot carrier while the needle is in the work, a work engaging knife mounted on the work support and presser foot carrier arranged to move with the work except when actuated to cut the work, and means for actuating the knife in the line of feed to cut the work while clamped between the work support and presser foot.

20. A sewing machine having, in combination, stitch forming and work feeding devices including a needle, an awl, a work support and a presser foot, means for actuating the work support and presser foot to clamp and feed the work, means for actuating the needle to feed the work during the back feed of the work support and presser foot, a work engaging knife arranged to move with the work while being fed by the needle, and connections from the awl actuating mechanism for actuating the knife in the line of feed to cut the work while clamped between the presser foot and the work support.

21. A sewing machine having, in combination, stitch forming and work feeding devices including a needle, an awl, a work support and a presser foot, two carriers to which said devices are connected arranged to reciprocate along the line of feed, the presser foot and work support being connected to one carrier and the needle being connected to the other carrier, mechanisms for actuating said devices and reciprocating said carriers to impart a continuous feeding movement to the work timed to back feed the work support and presser foot carrier while the needle is in the work, a work engaging knife mounted on the work support and presser foot carrier arranged to move with the work except when actuated to cut the work, and connections from the awl actuating mechanism for actuating the knife in the line of feed to cut the work while clamped between the work support and the presser foot.

22. A sewing machine having, in combination, stitch forming devices comprising a needle, an awl, a work support and a presser foot, two carriers to which said devices are connected, a connection between the carriers to cause one to be moved by the other, mechanism for reciprocating one of the carriers in the line of feed, and mechanism for

imparting a reciprocation to the carriers relative to each other in the line of feed.

23. In a machine provided with devices engaging the work intermittently to perform an operation on the work and feed the work, two carriers to which said devices are connected arranged to reciprocate along the line of feed, a connection between the carriers to cause one to be moved by the other, mechanism for reciprocating one of the carriers in the line of feed, and mechanism for imparting a reciprocation to the carriers relative to each other in the line of feed.

24. A sewing machine having, in combination, stitch forming and work feeding devices, including a work piercing needle, a work piercing awl, a work support and a presser-foot, means for actuating the presser-foot and work support to clamp and feed the work, means for actuating one of said work piercing instruments to feed the work during the back feed of the work support and presser-foot, a work engaging knife arranged to move with the work while being fed by said work piercing instrument, and means for actuating the knife in the line of feed to cut the work while clamped.

25. A sewing machine having, in combination, stitch forming and work feeding devices including a needle, an awl, a work support and a presser-foot, means for actuating said devices to feed the work continuously, a work engaging knife arranged to move with the work except when being actuated to cut the work, and means for actuating the knife in the line of feed to cut the work while clamped between the work support and presser-foot.

26. A sewing machine having, in combination, stitch forming and work feeding devices including a work piercing needle, a work piercing awl, a work support and a presser-foot, two carriers to which said devices are connected, arranged to reciprocate along the line of feed, the presser-foot and work support being connected to one of said carriers and at least one of said work piercing instruments being connected to the second carrier, mechanisms for actuating said devices and reciprocating said carriers to impart a continuous feeding movement to the work, timed to back feed the work support and presser-foot carrier while said last mentioned work piercing instrument is in the work, a work engaging knife mounted on the work support and presser-foot carrier arranged to move with the work except when being actuated to cut the work, and means for actuating the knife in the line of feed to cut the work while clamped between the work support and presser-foot.

In testimony whereof I have signed my name to this specification.

LAURENCE E. TOPHAM.
